(57) **CLAIM**

The ornamental design for a correction or marking roller, as shown and described.

DESCRIPTION

FIG. 1 is a front elevational view of a correction or marking roller according to the present invention;
FIG. 2 is a rear elevational view thereof;
FIG. 3 is a top plan view thereof;
FIG. 4 is a bottom plan view thereof; and,
FIG. 5 is a right side perspective view, the left side perspective view being the same as said right perspective side thereof.

1 Claim, 5 Drawing Sheets

FIG. 1

FIG. 2

FIG. 3

FIG. 4

FIG. 5
